[57] CLAIM

The ornamental design for a lap tray, as shown and described.

DESCRIPTION

FIG. 1 is a top, front and left side perspective view of a lap tray showing our new design;

FIG. 2 is a top plan view on a larger scale;

FIG. 3 is a front elevational view on a larger scale;

FIG. 4 is a bottom plan view on a larger scale;

FIG. 5 is a rear elevational view on a larger scale;

FIG. 6 is a left side elevational view on a larger scale, the side opposite is a mirror image thereof; and

FIG. 7 is a cross-sectional view thereof on a larger scale, taken on line 7—7 of FIG. 2.

FIG. 1.

FIG. 2.

FIG. 3.

FIG. 4.

FIG. 5.

FIG. 6.

FIG. 7.
